Thos. S. Chapman

United States Patent Office.

WALTER T. THORNTON, OF BELLEVILLE, MICHIGAN, ASSIGNOR TO HIMSELF AND ALEXANDER D. WRIGHT, OF SAME PLACE.

Letters Patent No. 71,821, dated December 3, 1867.

IMPROVEMENT IN ADJUSTABLE SEAT-FASTENER.

The Schedule referred to in these Letters Patent and making part of the same.

TO WHOM IT MAY CONCERN:

Be it known that I, WALTER T. THORNTON, of Belleville, in the county of Wayne, and State of Michigan, have invented a new and useful Wagon-Seat Fastening; and I do declare that the following is a true and accurate description thereof, reference being had to the accompanying drawings, and to the letters of reference marked thereon, and making a part of this specification.

Figure 1 is a front view of my invention ready to be attached to a wagon.

Figure 2 is a front view of the same, with the cap off, showing the rack and catch and spring.

The same letters refer to similar parts in each figure.

The object of my invention is to so construct a wagon-seat fastening, of any suitable material, that the seat may be raised and lowered at pleasure.

In manufacturing my invention, I make a plate, A, with suitable projections B B, &c., to which to fasten the cap C. Between the projections B B, &c., I place the rack D, provided at the top with a suitable rest, E, for the seat, which may be attached to the rest without or with springs, as may be desired. To the bed-plate A, I attach the catch F, which is made to retain its position by means of the spring G. These seat-fastenings I construct right and left-handed, as one is required upon either side of the wagon. The spring G may be a flat, a v-shaped, or a spiral spring, as may be most desirable.

What I claim as my invention, and desire to secure by Letters Patent, is—

The construction of a wagon-seat fastening, substantially as described, with plate A, projections B B, &c., cap C, rack D provided with seat-rest E, the catch F, and the spring G, or their equivalents, for the purpose set forth.

WALTER T. THORNTON.
